UNITED STATES PATENT OFFICE.

TRUMAN A. SMITH, OF MOBILE, ALABAMA.

STEERING-WHEEL LOCK.

1,265,540.

Specification of Letters Patent. Patented May 7, 1918.

Application filed December 29, 1916. Serial No. 139,568.

To all whom it may concern:

Be it known that I, TRUMAN A. SMITH, a citizen of the United States, residing at Mobile, in the county of Mobile and State 5 of Alabama, have invented new and useful Improvements in Steering-Wheel Locks, of which the following is a specification.

This invention relates to locks especially adapted to be used upon automobiles for the 10 purpose of locking the steering shaft with relation to the column which surrounds the same and it consists in the novel features hereinafter described and claimed.

An object of the invention is to provide a 15 simple and efficient means for securing the steering shaft of an automobile against turning movement during the absence of the owner of the machine or an authorized person. The said locking means is key operated 20 and the key is retained by the owner or the authorized person after the bolt of the lock is thrown and when the said owner or authorized person leaves the machine.

In the accompanying drawing:—

25 Figure 1 is a vertical sectional view of the lock.

Fig. 2 is a transverse sectional view of the same cut on the line 2—2 of Fig. 1.

30 Fig. 3 is a side elevation of the modified form of the device.

Fig. 4 is a fragmentary plan view of the form of device as shown in Fig. 3.

As illustrated in Figs. 1 and 2 of the drawing, the device includes a collar 1 which may 35 be secured to the foot board of an automobile in any suitable manner and which is provided at its upper portion with a casing 2. The column 3 is received in the collar 1 and the said column is provided at its side adjacent 40 the casing 2 with an opening 4. The steering shaft 5 is turnably mounted in the column 3 and the said shaft 5 is provided at its side with an opening 6 which is adapted to be moved into register with the opening 45 of the column 3. A bolt 7 is slidably mounted in the casing 2 and one end of the said bolt is received in the opening 4 of the column 3. A spring 8 is housed in the casing 2 and bears at one end against the side of the 50 collar 1 and at its other end against the shoulder 9 provided upon the bolt 7. The said spring 8 is under tension with a tendency to hold the bolt 7 in a retracted position in the casing 2.

55 A shaft 10 is rotatably mounted in the casing 2 and carries a cam 11 which is

adapted to engage the end of the bolt 7 when the said shaft is turned whereby the said bolt 7 is moved to a projected position against the tension of the spring 8 and the 60 end portion of the bolt is moved into the opening 6 when the same is in register with the opening 4 whereby the shaft 5 is locked against turning movement with relation to the column 3. The shaft 10 forms a part of 65 a lock 12 of conventional form and is best illustrated in Fig. 2 of the drawing, and the said lock includes tumblers 13 as indicated in dotted lines in Fig. 2 and the lock is adapted to be operated or manipulated by 70 means of a key 14. The bolt 7 is provided at its outer end with branches which lie at the opposite sides of the shaft and cam and serve to hold the parts in proper position with relation to each other. 75

When an owner or an authorized person leaves the automobile the key 14 is inserted in the lock 12 whereby the shaft 10 is turned and the bolt 7 is moved from a retracted position to a projected position with relation 80 to the casing 1 and the end of the bolt is moved into the opening 6. Thus the steering shaft is locked with relation to the column 3. When the owner or authorized person desires to use the automobile the key 85 4 is inserted in the lock 12 and the shaft 10 is turned so that the cam 11 is moved away from the bolt and under the influence of the spring 8 the bolt 7 is moved to a retracted position in the casing 2 and passes out of 90 the opening 6 thus rendering the shaft 5 free to rotate in the column 3.

In the form of the invention as illustrated in Figs. 3 and 4 of the drawing, a bracket 95 15 is attached to the dash board 16 of the automobile and the said bracket is provided with a casing similar to the casing 2 hereinbefore described and contains a bolt similar to that hereinbefore described and which is adapted to be operated by a key as described. 100 In other words, both forms of the invention are substantially alike with the exception that the casing 2 as shown in Figs. 1 and 2 is supported from a collar which is mounted upon the foot board while the corresponding 105 casing as shown in Figs. 3 and 4 is supported by a bracket 15 attached to the dash board of the machine.

From the foregoing description taken in conjunction with the accompanying drawing, it will be seen that a simple and substantial locking mechanism is provided for

securing the steering shaft of an automobile with relation to the column which receives the same and that the locking bolt may be easily and quickly moved by use of a key which is detachable from the device and hence an owner or an authorized person may use the mechanism and leave a machine standing in a public place with comparative safety.

10 Having described the invention what is claimed is:—

In combination with a steering shaft having an opening and a column having an opening, a casing mounted in a fixed position with relation to the column, a spring

retracted bolt slidably mounted in the casing and adapted to enter the said openings when the same are in register with each other, a shaft journaled in the casing and having a cam adapted to engage the bolt to move the same to a projected position, said bolt having branches which lie at the opposite sides of the shaft and cam whereby the cam and shaft serve as a guide for the bolt and the branches serve as a guide for the shaft, and a key operated lock located in the casing for controlling the movement of the shaft.

In testimony whereof I affix my signature.

TRUMAN A. SMITH.
